UNITED STATES PATENT OFFICE

2,356,521

SWITCH STRUCTURE

William B. Kochner, St. Louis, Mo., assignor to
 Knapp-Monarch Company, St. Louis, Mo., a
 corporation of Missouri

Application June 1, 1942, Serial No. 445,340

8 Claims. (Cl. 200—157)

My present invention relates to a switch structure particularly adaptable for electric drills and the like and designed for being built into the handle thereof.

One object of the invention is to provide a switch structure which minimizes the use of metal by its design, being almost entirely of Bakelite or any suitable insulating material or plastic, with only the current-carrying parts being formed of metal.

A further object is to provide a switch structure which is simple from the standpoint of the number of parts involved in its construction and easy to assemble and wire into the circuit of the device to be controlled thereby.

Another object is to provide an inexpensive switch structure which has snap action to minimize arcing at the contacts, and which has a number of design features so related as to accomplish all the necessary results involved, with a minimum of parts.

With these and other objects in view, my invention consists in the construction, arrangement and combination of the various parts of my device whereby the objects contemplated are attained, as hereinafter more fully set forth, pointed out in my claims and illustrated in the accompanying drawing, in which:

Figure 1 is a side elevation of my switch structure as applied to a handle of an electric drill or the like, parts of the handle being broken away and other parts being shown in section to show where the wires may enter and leave the handle;

Figure 2 is an enlarged vertical view through a portion of the handle and through my switch structure;

Figure 3 is an enlarged sectional view on the line 3—3 of Figure 1;

Figure 4 is a sectional view on the line 4—4 of Figure 2;

Figure 5 is a bottom perspective view of a switch actuator of my switch structure; and

Figure 6 is a sectional view similar to Figure 2, showing the parts in a different position.

On the accompanying drawing I have used the reference character H to indicate generally a housing in the form of a handle for an electric drill or the like. The handle H has a flange 10 for attachment to the motor of the drill and is provided with openings 12 and 14 for current wires to extend respectively into the handle from a source of current supply and from the handle to the electric drill. The handle H is hollow, being formed of Bakelite or other plastic material in two halves, parted vertically at the center,

and the two halves, after being formed, are retained in assembled relation to each other by rivets or bolts 15.

Each half of the handle H includes a side wall 16 and a top flange 17. The flanges 17 extend toward and contact with each other at the center of the handle and are retained in contact by the rivets or bolts 15. The parting line is shown at 18 in Figure 3, and the flanges 17 are not sectioned in Figures 2 and 6 to thereby indicate that the section in these figures is taken at the parting line.

A shelf element 19 extends inwardly from each side wall 16, and these shelf elements terminate spaced from each other, as shown in Figures 3 and 5, the space being indicated at 20. A pair of notches 21 is provided in each shelf element 19 to receive downwardly extending terminal ends 22 of stationary contact strips 23. The contact strips have down-turned terminal ends 24 notched as at 25 to receive circuit wires that are to be soldered thereto. The terminal ends 24, it will be noted, contact the ends of the shelf elements 19 whereby, in conjunction with the terminal ends 22 being confined in the notches 21, the contact strips 23 are confined against longitudinal movement relative to the shelf elements.

The side walls 16 are thickened as shown at 26 in Figure 4, and between the thickened portions 26 a switch actuator A is mounted for sliding movement. The sides of the actuator A are confined by the thickened portions 26, whereas the bottom of the actuator A slides on the shelf element 19 and the top thereof slides beneath the surfaces 27 of the flanges 17, which surfaces are parallel to the shelf elements 19. The switch actuator A has a thumb engageable portion 28 extending through a slot 29 in the handle H, such slot being formed by registering notches in the flanges 17. From the construction of the parts just described it will be obvious that the actuator A is confined to sliding movement along a predetermined axis, and is limited in such sliding movement by the ends of the notches 29.

The switch actuator A has a recess 30 in its bottom surface, thereby leaving end walls 31. The end walls 31 are notched, as at 32, the notches 32 being narrower than the recess 30. The notches 32 are slightly wider than the stationary contact strips 23 and straddle them to confine them against lateral movement on the shelf elements 19.

In the recess 30 I mount a movable contact strip 33 which is slightly less in width than the

width of the recess, slightly less in length than the length of the recess, and wider than the notches 32. The contact strip 33 has a pair of humps 34 to coact at times with humps 35 formed on the stationary contact strips 23. A spring 36 is positioned behind the movable contact 33 and is positioned in a socket 37 extending up into the thumb engageable portion 28 of the switch actuator. The movable contact 33 is thereby floatingly mounted in the recess 30 and biased to engage the contact strips 23.

Practical operation

In the operation of my switch structure, beginning with the closed circuit position of Figure 2, it will be noted that the humps 34 of the movable contact 33 are completely seated on the humps 35 of the stationary contacts 23. Accordingly, a circuit is established across the contacts 23 by the bridging contact 33.

When it is desirable to move the switch to "off" position the thumb engageable portion 28 is engaged and the switch actuator A thereby slid rearwardly. As illustrated in Figure 6, this causes the movable contact 33 to ride up on the humps 35 of the stationary contacts 23 until, finally, the right-hand end of the contact 33 leaves the hump 35 of the right-hand contact 23, thereby breaking the circuit. The break will be with snap action, because of the resistance to movement being encountered by the compression of the spring in Figure 6 until the movable contact is on the tops of the humps 35, whereupon there is no further tendency to raise the movable contact against the tension of the spring. The operator's thumb will accordingly move the actuator A quickly to the open circuit position because of this reduction in resistance to its movement. The open position of the switch is shown by dotted lines in Figure 2, wherein it will be noted that the central portion of the movable contact 33 is riding on top of the hump 35 of the left-hand stationary contact 23.

In closing the switch, the actuator A is moved forwardly of the handle H, causing contact to first be made between the right-hand end of contact 33 and the hump 35 of the right-hand contact 23 with a snapping of the switch to closed position after the position of Figure 6 is reached, and the spring 36 thereupon forces the humps 34 down over the humps 35.

Some changes may be made in the construction and arrangement of the parts of my device without departing from the real spirit and purpose of my invention, and it is my intention to cover by my claims any modified forms of structure, or use of mechanical equivalents, which may be reasonably included within their scope.

I claim as my invention:

1. In a switch structure for handles and the like, said handle constituting a housing for the switch structure and being formed in two parts with a cavity between said parts, said handle parts having shelf elements projecting toward each other, a pair of stationary contacts on said shelf elements, a switch actuator slideable on said shelf elements and confined between the shelf elements and the handle when the two parts of the handle are held assembled together, said switch actuator having a recess, and a movable contact mounted therein and adapted in one position of the switch actuator to bridge both of said stationary contacts.

2. In a switch structure for electric drills and

- the like, a handle for the drill formed in two parts with a cavity between said parts constituting a housing for the switch mechanism, said handle parts having shelf elements projecting toward each other, a pair of elongated stationary contacts on said shelf elements and having parts coacting therewith to prevent movement of said stationary contacts on said shelf elements, a switch actuator slideable on said shelf elements and being confined between the shelf elements and the handle, said switch actuator having guide notches straddling said stationary contacts to be guided thereby and having a recess, and a movable contact floatingly mounted therein and adapted in one position of the switch actuator to bridge said stationary contacts.
3. In a switch structure, a hollow handle formed in two parts and constituting a housing for the switch mechanism, said handle parts having shelf elements projecting toward each other, each of said shelf elements having a pair of notches, a pair of stationary contacts on said shelf elements having portions received in said notches when said two handle parts are assembled together, a switch actuator slideable between said shelf elements and a wall of the handle, said switch actuator having a recess, a floating contact mounted therein and adapted in one position of the switch actuator to bridge both of said stationary contacts and in the opposite position of the switch actuator to break contact between them, and a spring biasing said floating contact toward said shelf elements and said switch actuator toward said wall of the handle.
4. A switch structure for electric drill handles and the like formed in two parts with a cavity between said parts constituting a housing for the switch mechanism, said handle parts having shelf elements provided with registered notches, a pair of elongated stationary contacts on said shelf elements and each having parts received in said notches of said shelf elements to prevent lateral movement of the stationary contacts thereon, a switch actuator slideable on said shelf elements and confined between the shelf elements and said handle, said switch actuator having a recess and having guide notches straddling said stationary contacts and thereby guided for sliding movement, a movable contact in said recess for bridging coaction with said stationary contacts, said guide notches being narrower than said recess to prevent longitudinal movement of said movable contact within said recess relative to said switch actuator with the ends of said recess confining the ends of said movable contact, said switch actuator having a thumb engageable portion and said handle having a slot through which said thumb engageable portion extends to the exterior of the handle.
5. In a switch structure, a housing, said housing being formed in two parts with a shelf element projecting from each part and having registered notches, a pair of stationary contacts on said shelf elements having terminal ends received in said notches, a switch actuator slideable between said shelf elements and a wall of said housing, said switch actuator having a recess therein, a movable contact carried in said recess for bridging coaction with said stationary contacts, said switch actuator having a thumb engageable portion and said wall of the housing having a slot through which said thumb engageable portion extends to the exterior of the housing.
6. A switch structure comprising a two-part

housing having shelf elements projecting toward each other and provided with registering notches, a pair of stationary contacts each comprising a longitudinal body portion, a hump adjacent one end thereof and terminal ends bent downwardly therefrom, some of said terminal ends being received in said notches and others engaging the ends of said shelf elements to confine said stationary contacts against longitudinal movement on said shelf elements, a switch actuator slidable between said shelf elements and a wall of said housing, said switch actuator having guide notches coacting with said stationary contacts to retain them in proper alignment and having an enlarged recess between said notches, a movable contact in said recess and having a pair of humped portions to coact with the humped portions of said stationary contacts in the closed position of the switch, a spring in said recess behind said movable contact, said movable contact and said recess being wider than said notches to confine said movable contact against endwise movement relative to said switch actuator.

7. In a switch structure, a support, a pair of stationary contacts thereon, a switch actuator slidable on said support and having a recess therein adjacent said stationary contacts, a floating movable contact confined in said recess against lateral movement relative to said switch actuator, said stationary contacts and said movable contacts having coacting humps and depressions respectively, a spring in said recess and bearing against a portion of said movable contact intermediate said depressions and thereby tending to engage said movable contact with said stationary contacts, and means for confining said switch actuator to movement through a

limited space, one limit of the movement permitting said depressions of said movable contact to engage said humps of said stationary contacts and the other limit of movement permitting said movable contact to ride with said portion thereof supported on the hump of only one of said stationary contacts and with the backs of said depressions closely adjacent the bottom of said recess to thereby hold said movable contact against tilting.

8. A switch structure comprising a hollow handle being formed in two parts with a cavity between said parts constituting a housing for the switch mechanism, said handle parts having shelf elements projecting toward each other, a pair of elongated stationary contacts on said shelf elements and each having a hump and a terminal end substantially normal to the plane of the stationary contacts, said shelf elements having notches registering with each other and receiving said terminal ends when said two handle parts are assembled, a switch actuator slidably on said shelf elements and confined between the shelf elements and a wall of said handle, a movable contact carried by said switch actuator and having depressions to receive said humps when said movable contact bridges said stationary contacts, said movable contact in off position of the actuator being supported on only one of said humps, said actuator having a thumb engageable portion and said wall of each part of said handle having a second notch, said second notches registering to form a slot when said two parts are assembled through which said thumb engageable portion slidably extends to the exterior of the handle.

WILLIAM B. KOCHNER.
